ATTORNEY.

UNITED STATES PATENT OFFICE.

WALTER A. CROWDUS, OF CHICAGO, ILLINOIS.

STEERING-GEAR.

SPECIFICATION forming part of Letters Patent No. 703,552, dated July 1, 1902.

Application filed July 19, 1901. Serial No. 68,901. (No model.)

To all whom it may concern:

Be it known that I, WALTER A. CROWDUS, a citizen of the United States, and a resident of Chicago, in the county of Cook and State 5 of Illinois, have invented an Improved Steering-Gear Lock, of which the following is a specification.

This invention relates to steering gears or mechanisms, and relates particularly to steering-gears for motor-vehicles.

A primary object of the invention is to provide means, in combination with the steering-gear of a motor-vehicle, for locking said steering-gear in any desired adjustment, whereby 15 the vehicle can be steered more steadily than where the steering-handle alone is relied upon, particularly when passing over streets paved with cobble-stones or the like.

To this end the invention consists of a locking-bolt applied to the steering-gear and preferably adapted to be thrown to lock the steering-gear by means of the steering-handle.

The invention also consists of the various other features, combinations of features, and 25 details of construction hereinafter described and claimed.

In the accompanying drawings a steering-gear-locking device of my invention is fully illustrated.

30 Figure 1 is a sectional elevation of a steering-gear-locking device of my invention. Fig. 2 is a top plan view thereof, the handle being removed; and Fig. 3 is a top plan view, partly in section, of the steering-handle.

35 As regards its general features the steering-gear shown is of the general type heretofore patented to me by United States Letters Patent No. 598,314, dated February 1, 1898, said steering-gear being combined with a speed-regulating device, the vehicle being guided by lateral movement of said handle and its speed regulated by rotary movement thereof. The speed-regulating mechanism, however, forms no part of the present invention and is 40 merely shown incidentally, the following description being limited to the steering-gear.

45 Referring, then, to the drawings, A designates the steering-post, which is revolubly mounted in a bracket A', formed on a head A², secured to the upper end of a casing A³, secured in fixed position upon the vehicle-

frame, preferably to the vehicle-body. (Not shown.) The lower end of the steering-post A is connected to the pivoted front wheels of the vehicle in any suitable or approved manner, so that rotation thereof will impart similar pivotal movement to said wheels about substantially vertical axes. 55

The steering-handle A³ is pivoted to a head A⁴, secured to the upper end of the steering-post A in such manner that lateral movement of said steering-handle A³ will impart rotary movement to said steering-post A. As shown, said steering-handle A³ is tubular, and the rotary speed-regulating rod or shaft A⁵ is 60 mounted inside thereof, the hand-grip A⁶ being secured to the end of said rod A⁵, so that said shaft may be rotated and controlled thereby. 65

All of the foregoing elements are substantially similar to corresponding features shown and described in said prior patent No. 598,314 and will be readily understood from an examination of the drawings without a more detailed description thereof. 70

75 Formed in a plate or flange B on the bracket A' is a groove b, said groove being circular and concentric with the steering-post A. Mounted so as to be longitudinally movable in suitable bearings in a boss B' on the head 80 A⁴, directly beneath the steering-handle A³, is a lock-bolt B², which registers with the groove b and is adapted to be depressed into engagement with said groove by depressing the steering-handle A³. 85

In the preferable construction shown the groove b and the head of the lock-bolt B² are correspondingly tapered, so that depressing said lock-bolt will effect a strong frictional engagement between said lock-bolt and the 90 sides of said slot, which will effectually prevent rotation of the steering-post, and thus vibration of the wheels controlled thereby and relieving the hand of the operator from all jar due thereto. In the preferable construction shown, also, the lock-bolt B² is maintained normally retracted by means of a spring b', applied thereto. As shown, said spring b' is inserted between the end of a recess or chamber formed in the upper end of the boss B' and a head or cap b², removably secured to the upper end of the lock-bolt B². 95 100

As shown, also, the head or cap b^2 is fitted to the recess or chamber in the boss B' , thus forming a guide for the upper end of said lock-bolt.

5 With the described construction it is obvious that lateral movement of the steering-lever A^3 will change the direction of motion of the vehicle; also, that the steering-post A may be locked in any desired position by depressing the end of the steering-lever A^3 to force the lock-bolt B^2 into engagement with the groove b . When it is desired to release the lock-bolt B^2 , the steering-lever A^3 is raised, whereupon the spring b' will at once 10 retract the lock-bolt B^2 , or in case said spring is not sufficiently strong to break the frictional engagement between the lock-bolt B^2 and the sides of the groove b this can be effected by moving the steering-lever A^3 laterally, which will operate to break the engagement of said lock-bolt with said groove, whereupon said spring will at once retract said bolt.

I claim—

25 1. In a steering-gear, the combination with a steering-post, of a lock-bolt carried thereby, a fixed support, a groove therein adapted to be engaged by said lock-bolt and means to advance said lock-bolt into engagement with said groove, substantially as described.

2. In a steering-gear, the combination with a steering-post, of a lock-bolt carried thereby, a fixed support, a groove therein adapted to be engaged by said lock-bolt, said groove and lock-bolt being correspondingly tapered, and means to advance said lock-bolt into engagement with said groove, substantially as described.

3. In a steering-gear, the combination with a steering-post, of a lock-bolt carried thereby, a fixed support, a groove formed therein adapted to be engaged by said lock-bolt, a spring applied to said lock-bolt adapted to maintain the same normally retracted and means to advance said lock-bolt into engagement with said groove, substantially as described.

4. In a steering-gear, the combination with a steering-post, of a lock-bolt carried thereby, a fixed support, a groove formed therein adapted to be engaged by said lock-bolt, said lock-bolt and groove being correspondingly tapered, a spring applied to said lock-bolt adapted to maintain the same normally retracted and means to advance said lock-bolt into engagement with said groove, substantially as described.

5. In a steering-gear, the combination with a steering-post and a steering-lever pivoted thereto, of a lock-bolt carried by said steering-post beneath said steering-lever so as to be depressed thereby, a fixed support and a groove formed therein adapted to be en-

gaged by said lock-bolt, substantially as described.

6. In a steering-gear, the combination with a steering-post and a steering-lever pivoted thereto, of a lock-bolt carried by said steering-post beneath said steering-lever so as to be depressed thereby, a fixed support and a groove formed therein adapted to be engaged by said lock-bolt, said lock-bolt and groove being correspondingly tapered, substantially as described.

7. In a steering-gear, the combination with a steering-post and a steering-lever pivoted thereto, of a lock-bolt carried by said steering-post beneath said steering-lever and adapted to be depressed thereby, a fixed support, a groove therein adapted to be engaged by said lock-bolt and a spring applied to said lock-bolt adapted to maintain the same normally retracted, substantially as described.

8. In a steering-gear, the combination with a steering-post and a steering-lever pivoted thereto, of a lock-bolt carried by said steering-post beneath said steering-lever and adapted to be depressed thereby, a fixed support, a groove therein adapted to be engaged by said lock-bolt, said lock-bolt and groove being correspondingly tapered, and a spring applied to said lock-bolt adapted to maintain the same normally retracted, substantially as described.

9. In a steering-gear, the combination of a fixed support, a steering-post revolvably mounted therein, a head on said steering-post, a steering-lever pivoted to said head, a lock-bolt mounted in said head beneath said steering-lever and adapted to be depressed thereby, and a groove in the fixed support in which said steering-post is mounted adapted to be engaged by said lock-bolt, said lock-bolt and groove being correspondingly tapered, substantially as described.

10. In a steering-gear, the combination of a fixed support, a steering-post revolvably mounted therein, a head on said steering-post, a steering-lever pivoted to said head, a lock-bolt mounted in said head beneath said steering-lever and adapted to be depressed thereby, a groove in the fixed support in which said steering-post is mounted adapted to be engaged by said lock-bolt, said lock-bolt and groove being correspondingly tapered, and a spring applied to said lock-bolt and adapted to maintain the same normally retracted, substantially as described.

In testimony that I claim the foregoing as my invention I affix my signature, in presence of two subscribing witnesses, this 16th day of July, A. D. 1901.

WALTER A. CROWDUS.
